UNITED STATES PATENT OFFICE.

HARMON P. ELLIOTT, OF CAMBRIDGE, MASSACHUSETTS.

STENCIL-PRINTING MACHINE.

Application filed January 24, 1924. Serial No. 688,298.

To all whom it may concern:

Be it known that I, HARMON P. ELLIOTT, a citizen of the United States, residing in Cambridge, in the county of Middlesex and 5 State of Massachusetts, have invented an Improvement in Stencil-Printing Machines, of which the following is a specification.

This invention relates to printing machines wherein the printing characters are 10 borne by stencils and has particular reference to a hand operated stencil printing machine.

For many purposes, it is desirable to duplicate the printing or make multiple 15 prints of certain characters, as a name and address, upon separate portions of the same sheet or upon different sheets. Various bills for instance, require a name and address to be printed upon a detachable portion or stub 20 of the bill sheet and also the same name and address upon the main body of the bill sheet.

This invention relates to and has as an object to provide a stencil printing machine, 25 and particularly a hand operated stencil printing machine, with means whereby the machine may be operated to make a single impression from each stencil and also a plurality of impressions from a single 30 stencil.

It is a further object to provide means associated with a hand operated stencil printing machine, and as an attachment therefor, to enable the repeated printing of the characters borne by a single stencil. 35

In carrying out the invention, means are or may be provided to move the stencils and the sheets to be printed upon simultaneously while recording on the sheets the impression 40 of the characters borne by the stencils; and means to cause a selected stencil, or all of the stencils, in succession, to be returned to the initial printing position for a second printing of the impression carried by the 45 stencil. Means may be provided whereby the stencil may be returned to its initial printing position while the sheet to be printed upon is held without movement whereby the same characters may be multiplied on 50 the same sheet by successive operations of the machine.

A further object is generally to improve the construction and operation of stencil printing machines and particularly hand 55 operated stencil printing machines.

Fig. 1 is a side elevation of a hand operated stencil printing machine embodying the invention.

Fig. 2 is a plan view of Fig. 1.

Fig. 3 is a vertical sectional detail taken 60 along line 3-3 of Fig. 1.

Fig. 4 is a detail of the latch support for the operating handle.

Fig. 5 is a plan detail partly in section illustrating more particularly the repeating 65 device embodying the invention in position to return a stencil from which an impression has been made into position to record another impression.

Fig. 6 is a sectional detail taken along line 70 6-6 of Fig. 5, and illustrating more particularly the stencil retriever.

Fig. 7 is a detail side elevation illustrating the stencil retriever part way on its return movement and with a stencil carried by it. 75

Fig. 8 is a detail illustrating more particularly the means for disconnecting the stencil feeding mechanism from the stencil moving and printing mechanism.

Fig. 9 is a detailed sectional elevation il- 80 lustrating the relative positions of the printing rolls and a stencil engaged by the stencil retriever in position for imprinting duplicate impressions from the stencils.

Fig. 10 is a view similar to Fig. 9 but 85 showing the relation of the various parts of the apparatus at the end of the first printing operation and with the stencil retriever in position to return the stencil for a second printing operation. 90

Fig. 11 is similar to Fig. 9 but shows the relation of the various parts of the device with the stencil in partially printed position within the printing rolls and with the pusher in readiness to deliver a second stencil into 95 the track.

Fig. 12 is a perspective detail illustrating more particularly the construction of the dating sector.

Fig. 13 is an enlarged detail of the latch 100 for preventing return movement of the stencils in the stencil track.

Fig. 14 is an enlarged detail of the hooked end-portion of the connecting rod.

As here shown, the hand operated stencil 105 printing machine embodying the invention comprises a base 10 which is adapted to rest upon a table or other suitable support. Said base 10 is formed with a flat top 11 which forms a table or bed adapted to support the 110

work sheets, as envelopes, bills, and the like to be printed.

- The type of stencil more particularly adapted for use in this machine is shown 5 most clearly in Fig. 5 and comprises a relatively stiff frame 12 having a window therein occupied by a stencil sheet 13, which sheet is adapted to bear the characters to be imprinted. Said stencil sheet 12 is disposed 10 to lie entirely within the opposite faces of the frame 12 as is indicated more clearly in Fig. 6, although the particular form of stencil is not of especial importance so far as this invention is concerned.
- 15 The stencils are adapted to be moved above the bed 11 in parallel and spaced tracks 14 and 15 which tracks are formed or provided with grooves 16 in their opposed parallel faces, in which grooves the 20 stencils are adapted to slide freely. A superimposed pile of stencils are adapted to be supported in position to be introduced one at a time into one end of the stencil track whereby to be moved 25 along said track for the printing of the impressions carried by them. The stencils are contained in a stencil holder carried by and disposed at one end of the stencil track. The stencil holder may comprise the channelled end-plates 18 and 19, which plates may 30 be secured to the stencil tracks 14 and 15 by suitable means as screws 20, and said stencil holder thereby serves to provide a rigid support for the tracks.
- 35 A supporting bracket 21 may be secured to the base 10 of the machine at one side thereof, and extend upwardly and over the bed 11 of said base and be secured to one of said tracks as the track 15 whereby to 40 support the track and the stencil holder in elevated position above and spaced from said bed 11. A superimposed pile of stencils is adapted to be supported freely within said stencil holder and in such position that the 45 lowermost stencil of the pile may be transferred from the pile into and moved along the track into a printing position.
- The printed stencils are adapted to be discharged from the track into a stencil receiver 50 23, which receiver is pivotally connected dependently with the ends of said tracks 14 and 15 as by means of a bracket 24; and said stencil receiver may be swung upwardly 55 into an inverted position above said tracks and bracket as illustrated in dotted lines, Fig. 1, when the machine is not in use.
- The printing mechanism includes two superimposed stencil driving and printing sectors 25 and 26, which sectors are approximately 60 semicircular in shape and the faces thereof may be covered with a relatively yielding material as rubber, for instance. The lower sector is fixed to an operating shaft 27 and said sector may extend through 65 an aperture 28 in the bed 11 of the base 10.

Said operating shaft 27 is journaled in a lever support 29, which support is pivoted at 30 to the base 10. The other end of said lever support is engaged by a compression spring 31 whereby yieldingly to maintain 70 the printing sector 26 in printing relation with the stencils in the stencil tracks and also with the work to be printed upon and permit said sector to yield downwardly whereby to compensate for various thicknesses of the work. Said operating shaft 75 27 is extended freely through a vertically elongated aperture 33 in the base 10 and a gear 34 is fixed to the outer end thereof. The upper sector 25 is fixed to an operating 80 shaft 35 and said shaft is supported in the spaced arms 36 and 37 of a bracket 38, which bracket is secured to the base 10. A gear 39 is fixed to the end of said shaft and meshes with the gear 34 and is of equal pitch diameter therewith whereby both sectors may be 85 rotated at the same peripheral speed.

An arm 40 is fixed to said gear 39 to provide means by which the printing sectors may be rotated. Said arm is provided with 90 a detachable connection with the operating handle 41. Said operating handle is carried loosely on the extended end of the upper shaft 35 beyond said arm 41. Said handle is provided with an intermediate cylindrical 95 portion 43, which portion may form a crank arm, and a spring-pressed pin 44 is slidably received within said cylindrical portion 43. Said pin is adapted to enter a recess in the end of said arm 40 whereby to lock said 100 arm and handle releasably for conjoint rotation. Said arm may be released from said handle by moving said pin 44 toward the right, Fig. 3, whereby to remove the end of said pin from position within the recess in said arm 40 and the handle may then be rotated independently of said sectors whereby the stencils may be fed between said sectors without being printed therefrom and for a purpose with which this invention 110 is not concerned.

A pivoted latch 46 is secured to the bracket 38 and is adapted to support said arm 40 against counter-clockwise rotation; yet said latch is constructed and arranged, 115 in an obvious manner, to permit the arm to rotate in a clockwise direction.

Stencils are adapted to be fed successively from the pile of stencils in the stencil receiver and delivered into the stencil tracks 120 in a position to be engaged by the printing sectors by suitable means including the pusher 50. Said pusher is arranged to be reciprocated within the slots in the tracks 14 and 15 and to engage the lowermost stencil 125 of the pile and move it from its position under the pile of stencils and into such position in the track that it may be engaged by the sectors 25 and 26, as said sectors are rotated, which sectors are arranged to move 130

the stencils further along the track while recording the impressions borne by the stencils. Said pusher may be reciprocated by suitable means including a connecting rod

52, which connecting rod preferably is made in two independent sections which are or may be adjustably connected together intermediate the ends of the connecting rod, as at 53, whereby to permit the pusher 50 to 10 be adjusted with respect to the stencil pile.

In accordance with this invention, said connecting rod is arranged for detachable operative connection with the operating handle 41. For this purpose, the free end of 15 said connecting rod is formed or provided with a depending portion 55 which terminates in a lower and more or less semi-circularly arranged hook-portion 56. Said hooked end portion of the connecting rod is 20 adapted to fit over the cylindrical portion 43, or crank arm, of the operating handle 41, which cylindrical portion is formed or provided with a peripheral groove in which the hooked end portion of the connecting 25 rod is received removably. When said connecting rod is in operative engagement with the operating handle, the hooked end portion of said connecting rod is adapted to be received on the cylindrical portion 43 of 30 said operating handle 41 as is indicated more clearly in Fig. 12.

A pin 57 is extended approximately horizontally through the depending portion 55 of said connecting rod into a position just 35 above the cylindrical section 43 of the operating handle whereby normally to restrain said connecting rod and handle in the relation shown. Said pin 57 is arranged to be retained yieldingly in such position 40 by suitable means as the spring 58. The connecting rod is arranged to be disconnected from the handle by depressing the connecting rod upon said handle thereby to press said spring 58 outwardly and cause 45 the handle to be released from the hooked end portion of the connecting rod. The space between the hooked end portion of the connecting rod and the body of the rod is adapted to be sufficient to permit the handle to be rotated out of the hooked end portion and without reciprocating the connecting rod, the body of the connecting rod merely resting upon the handle and rising 50 and falling therewith without being reciprocated to actuate the pusher.

As thus arranged, with the connecting rod in operative connection with the operating handle, the pusher 50 is given one complete reciprocation at each complete revolution of the handle, whereby to move the lowermost stencil from the pile of stencils into the stencil track and in a position to be engaged and moved further along the track by the sectors 25 and 26. Said sectors are so arranged and timed with rela-

tion to the movements of the pusher as to engage a stencil moved into the track from the stencil receiver and move it along the track while the pusher is on its outward stroke.

70 The operation of the machine so far described is substantially as follows:

The work sheet as an envelope or bill to be printed upon is placed upon the bed 11 of the machine beneath the tracks 14 and 15 75 and between the sectors 25 and 26. As said sectors are rotated, the proximate ends thereof are moved inwardly toward each other and into engagement with the sheet and also with the stencil superimposed thereon in said stencil track; and press the two together. Due to the rotation of said sectors, the stencil and the sheet are moved simultaneously toward the delivery end of the machine and, at the same time, the impressions borne by the stencil are impressed 80 on the sheet by ink carried by the face of the upper stencil 25 which ink is forced through the impression in the stencil.

The initial position of the sheet to be 85 printed upon may be fixed by a side guide 60, which guide may have a slot 61 therein through which a clamping screw 62 is adjustably received; and said screw may be screw-threaded removably in any one of a 90 series of aligned and spaced apertures 63 in said bed 11. The sheet may be positioned relative to the stencil track by the top guide 65, which guide is or may be slidable in grooves 66 contained in the bed 11. A 100 clamping bar 68 may be secured to said guide 65 and extended over one of the stencil tracks as the track 15. A resilient clamping member 69 may extend over said guide bar 68 and a clamp screw 70 may serve to clamp said 105 guide bar 68 releasably to the stencil track 16 in adjusted positions of said bar whereby to maintain said top guide in adjusted positions thereof.

The surface of the upper sector may be 110 maintained in inked condition by suitable means as the ink roll 73. Said roll is supported in position above said upper sector 25 by the bracket 38 and is rotatable in said bracket. Said ink roll may be raised free 115 from or lowered into engaging position with said sector 25 by a suitable means as an eccentric bushing 74, which bushing is rotatably mounted in said bracket 38 and is arranged eccentrically to support the ink roll 120 73. Said bushing is provided with a handle 75 by which the bushing may be rotated to raise or lower the ink roll.

Ink may be contained in ink reservoir 77, 125 which reservoir is pivotally supported by the stencil receiver. A toothed ink wheel 78 is rotatably mounted within said ink reservoir, and with the periphery thereof immersed in the ink. A transfer roll 80, which preferably is of felt or other absorbent ma- 130

terial, is disposed above said ink reservoir and is adapted to be held yieldingly against and in rolling engagement with the ink roll 73 whereby to be rotated as the printing sector 25 rotates said ink roll. Ink may be applied to the transfer roll by moving said ink roll 70 upwardly, whereby to cause the ink wheel 78 to engage and roll in engagement with said transfer roll. Said transfer roll 10 is rotatably supported by a bracket 83, which bracket is pivotally supported on the upper operating shaft 35. A spring 84 connected between said bracket 83 and the fixed bracket 38 serves to maintain said transfer roll 15 80 yieldingly in engagement with the ink roll 73.

A protective cover 86 may be pivoted to the stencil track and extended upwardly and over said ink roll 73 and transfer roll 83 20 whereby to enclose both and protect the surfaces thereof from accumulation of dust. Said cover may be moved about its pivot toward the left, Fig. 1, whereby to expose said rolls for inspection.

25 In accordance with this invention means in addition to the construction above set forth are provided to cause the stencils or any selected stencil to be returned repeatedly at will, into a position to be re-engaged 30 by the sectors 25 and 26 whereby to provide for making multiple imprints of the impressions borne by the stencils. Said stencil retriever is adapted to be associated detachably with one of the stencil tracks as track 35 14 and to be slidable thereon in response to movements of the stencils within the tracks and also in response to a retractile means as 40 a spring. Said stencil receiver includes the superposed and spaced upper and lower arms 90 and 91 which are preferably integral with the end connecting and separating portion 92. Said arms 90 and 91 are 45 adapted to be disposed on opposite sides of the stencil track 14 and slide freely therealong in engagement therewith.

Said end connecting and separating portion 92 is provided with an upwardly reflexed shoulder portion 93 or is otherwise arranged to guide said retriever for movements along said track and prevent unintentional detachment therefrom; and said end connecting and separating portion 92 may be shaped to provide resiliency to said arms 50 90 and 91. Said arms, however, are adapted 55 to be sufficiently resilient to permit said member to be applied to or detached from the track.

The free ends of said arms 90 and 91 are 60 adapted to extend inwardly beyond the inner face of the stencil track 14 and said arms are reflexed toward each other as at 90^a and 91^a. Said reflexed end portions 90^a and 91^a are adapted frictionally to engage yieldingly 65 with the frames 12 of the stencil as they are moved along the track. Said stencil re-

triever is formed or provided with an upwardly extended arm 95, which arm has a slot 96 therein in which one end of a retractile spring 97 is detachably received.

Said retractile spring is extended along 70 and disposed above said track 14 and the other end of said spring is secured detachably in a slot 98 of a support 99, which support may be secured preferably removably to the stencil holder by suitable means as the screw 100. A forward stop member as the screw 101 is secured to the stencil track 14 in the path of forward movement of said stencil retriever whereby to limit the extent of such movement; and the stencil holder is 75 adapted to form a rear stop-member which is arranged to limit the return movement of the stencil retriever under action of said spring.

When the stencil retriever is in operative 80 position on the stencil track 14 as illustrated more particularly in Fig. 5 and stencils are moved along the stencil track by reason of the conjoint operation of the pusher 50 and the driving and printing sectors 25 and 26, 85 the friction between the stencils and the stencil retriever serves to move said retriever along the track into a position against said stop member 101 and said retriever will be 90 held in said position inasmuch as stencils are normally prevented from moving backward in the track either by being engaged by said sectors 25 and 26 or by the pusher 50. When the stencil retriever is in its forward 95 position and the pusher is at the inner end of its stroke, and the sectors 25 and 26 are separated, the arrangement is such that said retriever engages but one stencil, and there 100 is but one stencil disposed in the track between said retriever and the stencil holder. 105

Said stencil retriever is brought into action to cause the repeated printing of the characters borne by any selected stencil in combination with the means providing for disconnecting the connecting rod 52 from 110 operative engagement with the operating handle 41. The operation of the device is or may be substantially as follows:

Normally the connecting rod 52 is arranged in operative connection with the handle 41 as indicated more particularly in Fig. 8, which figure illustrates the relative position of the handle and connecting rod with the driving sectors in spaced relation or as shown in Fig. 9 and with the pusher at the inner end of its stroke and beneath the pile of superimposed stencils in the stencil receiver. 115

As thus arranged, each complete rotation of the handle will cause a stencil to be fed from the stencil receiver and delivered to the sectors 25 and 26 and impressions recorded from said stencils in the usual manner. 125

The stencil retriever will occupy a position against its stop member 101 as shown in 130

Fig. 5, being moved to and held in such position by its engagement with and the movement of the stencils. When, however, a duplicate impression of a stencil is to be recorded, the connecting rod 52 is depressed to cause it to be released from the operating handle; and said connecting rod may then occupy some position as that illustrated in dotted lines Fig. 8. As thus arranged, the 10 pusher 50 will not be operated when the handle is rotated, although the printing sectors 25 and 26 will rotate. Upon the rotation of the operating handle, the sectors will be caused to engage the stencil disposed between the stencil retriever and the stencil receiver and will move that stencil forwardly in the track and print therefrom. This stencil will be also moved into the stencil retriever and cause the forward stencil to be 15 displaced therefrom. A complete rotation of the operation handle 41 when disconnected from the pusher thereby effects the first printing of the stencil from which multiple impressions are to be made. Inasmuch 20 as during this revolution of the operating handle the pusher 50 has been inoperative by reason of the disconnection of the connecting rod from its handle no stencil has been delivered into the track from the stencil receiver. Consequently, when the sectors 25 and 26 have moved the stencil into substantially the position illustrated in Fig. 5 and have released the stencil, said stencil and the stencil retriever are free to move rearwardly 25 along said track by reason of the retractive effort of the spring 97 and consequently the stencil is again moved into its original printing position and comes to rest against the inner end of the pusher. If but one extra 30 impression is to be made from the stencil, the connecting rod 52 is raised upwardly, when the handle is in the position shown in Fig. 8, whereby to cause the connecting rod to be operatively connected with the handle. 35 On a second rotation of the operating handle, the retrieved stencil is again moved forwardly by reason of its engagement with the printing sectors and the second impression is made from said stencil. As the operating 40 handle is rotating throughout the upper half of its clockwise movement the pusher 50 is being moved outwardly into position to engage and deliver a stencil from the stencil holder. During the lower half of the rotation of the operating handle, the pusher is moved inwardly and thereby delivers a fresh stencil into the stencil track. This fresh stencil is caused to engage with the stencil in the stencil retriever, thereby to hold said 45 stencil from being again returned so that upon the second rotation of the operating handle, the fresh stencil is engaged by the printing sectors and moved forwardly to displace from the stencil retriever the stencil 50 from which duplicate impressions have been recorded. If further impressions from a single stencil are desired, the operating handle may remain disconnected from the connecting rod for a sufficient number of complete revolutions of said operating handle to permit the required number of impressions to be recorded; and the stencil will be retrieved by the stencil retriever as many times as multiple prints are desired. If duplicate impressions are desired from every stencil contained in the stencil holder, as for the printing of certain types of bills for instance, the connecting rod will be disconnected from and subsequently connected to the operating handle at every alternate complete revolution thereof. 55

It will be noted that while a stencil may be returned into the printing position by the stencil retriever, the sheet on which the impressions are recorded is not returned but is maintained in position to which it has been moved by the printing sectors and for the reason that the stencil retriever engages the stencil alone and not the sheet printed upon. During the second printing operation from the same stencil, however, the sheet is again engaged by the sectors, along with the stencil, and both are moved forwardly simultaneously while the second printing impression is being recorded. 60

There is a certain part of the operation of the machine when the stencils in the stencil track are free from engagement with the sectors 25 and 26 and the pusher is moving outwardly. Inasmuch as the stencil retriever tends at all times to move the stencils in the track backwardly toward the stencil holder, the stencils may become displaced from proper position. To prevent this backward movement, a spring pressed latch 108 (Fig. 13) is disposed adjacent the stencil holder and in position releasingly to engage the rear edge of the stencils as they emerge from the stencil holder and prevent such backward movement, while not restricting the forward movement of the stencils. Said latch may be desirable when multiple impressions are to be recorded of but certain stencils, but ordinarily is not necessary, when but single impressions are to be recorded, or when multiple impressions of every stencil are to be recorded. 65

In connection with the means for providing for the printing of a plurality of impressions from the same stencil, means are also provided for imprinting identical characters as, for instance, a date, upon all the sheets adapted to bear the stenciled characters; and the dating device is or may be arranged to print the date each time an impression of the characters borne by each stencil is made and also each time a duplicate impression is made from the stencils. The dating device includes a sector 110 which sector is formed or provided with an 70

115

120

125

130

arcuate T slot 111 in the peripheral face thereof, which slot is adapted to receive type slugs 112. Said sector 110 is formed or provided with a semi-circular hub 113, which hub preferably is extended laterally on one side only of the sector. Said hub is formed with a semi-circular recess 114 which recess is adapted to receive the upper operating shaft 35. The semicircular hub 116 is fixed 10 to said shaft 35 between the arms 36 and 37 of the bracket 38 and said hub may be complementary to the hub 113 of said date sector 110.

Said date sector preferably is detachably received on said shaft 35 between said arms 36 and 37 and in substantial alignment with the hub 116. An open ended circular spring member 117 is received over said fixed hub 116 and the hub 113 of said date sector 20 and thereby serves to secure said date sector detachably in driving position on said shaft 35. Said date sector may be removed for change of type by removing said spring member 117. A platen sector 115 may be 25 fixed permanently to the lower operating shaft 27 and 30 disposed thereon as to support the sheet to receive the date borne by the date sector.

The type carried by said date sector may 30 be inked by means of an ink roll 120, which ink roll is disposed between said date sector and the stencil holder; and is rotatably mounted on the bracket 83. Said ink roll 120 may be composed of felt or other porous 35 and ink absorbent material and is adapted to be engaged by the type on said type sector as the sector is rotated. Said ink roll is adapted to retain a sufficient quantity of ink to render unnecessary the re-inking of the 40 roll except at extended intervals. Said date sector is so arranged on the operating shaft 35 that both the date and the characters borne by the stencils are imprinted simultaneously upon the sheet. If the machine is 45 so operated that but a single impression is made of the stencils and a new sheet is disposed on the bed 11 of the machine and under the stencil track for each impression, then but a single date impression will be recorded on a single sheet. If, however, the 50 stencil retriever is brought into action, a date impression will be made upon the sheet, at spaced intervals thereon, each time an impression is made from the same stencil.

55 A counting device may be associated with the machine above described whereby to record automatically the number of times impressions have been made thereby to record the number of pieces of work printed upon. 60 The counting device 130 may be fixed to a suitable part of the frame of the machine and may have a flexible arm 131 attached to its movable component. Said arm is disposed within the path of movement of the 65 arm 40 attached to the upper operating shaft

35, and said flexible arm 131 is adapted to be engaged at each revolution of said arm 40 whereby to actuate the counting device.

The structure may be otherwise modified without departing from the spirit of the invention.

I claim:

1. A stencil printing machine comprising means to advance stencils in successive order toward a printing position and means to move a selected stencil repeatedly into and out of such printing position including means to disable said stencil-advancing means.

2. A stencil printing machine comprising means to advance stencils in successive order toward a printing position and means to move a selected stencil repeatedly into and out of such printing position including means to disable said stencil-advancing means, and means to advance a sheet progressively forward through said printing position.

3. A hand-operated stencil printing machine including means to advance stencils in successive order toward a printing position, means to receive a sheet to be printed upon in printing relation with a stencil, a printing device arranged to engage and print from said successively-advanced stencils, and means to make multiple prints from a selected stencil including means to move the sheet forward to present a fresh surface to be printed upon, and means to retract a used stencil into a position to be again operatively engaged by said printing device.

4. A hand-operated stencil printing machine including means to deliver stencils in successive order to a printing position, means to receive a sheet to be printed upon in printing relation with a stencil, a printing device arranged to engage and print from said successively-delivered stencils, and means to make multiple prints from a selected stencil including means to arrest the action of said stencil delivery means, means to move the sheet to present a fresh surface to be printed upon, and means including said printing device to move the same stencil successively into and out of printing position.

5. A stencil printing machine including means to deliver stencils in successive order to a printing position, means to receive a sheet to be printed upon in printing relation with a stencil, a printing device arranged to engage and print from said stencils, and means to make multiple prints from a selected stencil including means to disable the stencil delivery means, means to present the selected stencil to be engaged successively by said printing device, and means to move the sheet to be printed upon during each printing operation.

6. A stencil printing machine including means to deliver stencils in successive order

- to a printing position, sheet-moving means, a printing device arranged to engage and print from said stencils, and means to make multiple prints from a selected stencil including means to disable the stencil delivery means, means to move the selected stencil repeatedly into position to be engaged by said printing device, and means to actuate said sheet-feeding means for each impression 5
- 10 made of the stencil.
7. A stencil printing machine including means to engage a stencil and the work to be printed upon and move both simultaneously in engagement with each other while recording the stencilled characters on the work, means normally arranged to deliver stencils in successive order in position to be engaged by said stencil printing means, and means to make a second print of a selected stencil. 15
- 20 8. A stencil printing machine including means to engage a stencil and the work to be printed upon and move both simultaneously in engagement with each other while recording the stencilled characters on the work, means to deliver stencils in successive order in position to be engaged by said stencil printing means, and means to make a second print of a selected stencil, including means to return the selected stencil into its initial 25 position to be again engaged and moved forwardly by said stencil printing means.
9. A stencil printing machine including means to engage a stencil and the work to be printed upon and move both simultaneously in engagement with each other while recording the stencilled characters on the work, means to deliver stencils in successive order in position to be engaged by said stencil printing means, and means to make a second 30 print of a selected stencil including means to hold the work in its moved position, and means to retrieve the selected stencil into its initial position to be again engaged and moved forwardly by said stencil printing means. 35
- 40 10. A stencil printing machine including means to engage a stencil and the work to be printed upon and move both simultaneously in engagement with each other while recording the stencilled characters on the work, means to deliver stencils in successive order in position to be engaged by said stencil printing means, and means to make a second print of a selected stencil including means to disable said stencil delivery means and means to return the selected stencil into its initial 45 position to be again engaged and moved forwardly by said stencil printing means.
11. A stencil printing machine including means to engage a stencil and the work to be printed upon and move both simultaneously in engagement with each other while recording the stencilled characters on the work, means to deliver stencils in successive order in position to be engaged by said stencil 50
- 55 60 65
- printing means, and means to make a second print of a selected stencil, including means to disable said stencil delivery means, means to return the selected stencil into its initial position to be again engaged and moved forwardly by said stencil printing means, and means to hold the work in its moved position during the return movement of the stencil. 70
12. A stencil printing machine having the combination of superimposed stencil driving and printing rolls arranged to engage a stencil and the work to be printed upon and move both simultaneously in engagement with each other while recording the stencilled characters on the work, and thereafter release said stencil, means to deliver stencils in successive order into position to be engaged by said rolls, and means to make multiple prints of a selected stencil including means to disable said stencil delivery means, and means to return the selected stencil again into position to be engaged by said rolls and moved forwardly. 80
13. A stencil printing machine having the combination of superimposed stencil driving and printing sectors arranged to engage a stencil and the work to be printed upon and move both simultaneously in engagement with each other while recording the stencilled characters on the work, and thereafter release said stencil and the work, means to rotate said sectors, means to deliver stencils in successive order into position to be engaged by said sectors, and means to make multiple prints of a selected stencil including means to disable said stencil-delivery means, means to return a printed stencil between and free from driving engagement with said sectors into position to be again engaged and moved forwardly by said sectors. 90
14. A stencil printing machine having the combination of superimposed stencil driving and printing sectors arranged to engage a stencil and the work to be printed upon and move both simultaneously in engagement with each other while recording the stencilled characters on the work, and thereafter release said stencil and the work, means to rotate said sectors continuously to deliver stencils in successive order into position to be engaged by said sectors, and means to make multiple prints of a selected stencil including means to disable said stencil delivery means, means to return a printed stencil between said sectors while said sectors are free from driving relation with the stencils and into a position to be again engaged and moved forwardly by said sectors. 100
15. A stencil printing machine having the combination of superimposed driving and printing sectors arranged to engage a stencil and the work to be printed upon for approximately half a revolution of said sectors 110
- 115
- 120
- 125
- 130

- and move the stencil and work simultaneously in engagement with each other while recording the stencilled characters on the work, and release and be free from engagement with the stencils and the work during the remaining portion of a complete revolution of said sectors, means to rotate said sectors in unison, means to deliver stencils in successive order into position to be engaged by said sectors, and means to make multiple prints of said stencils including means to disable said stencil delivery means, and means to return a printed stencil between said disengaged sectors and into a position to be again engaged by and moved forwardly of said sectors while retaining the work against return movement. 16. A stencil printing machine including the combination of a stencil track, means to move stencils in successive order into said track, superposed driving and printing sectors disposed on opposite sides of said track in position to engage the stencils therein and drive them therealong while printing from the stencils, and means to make multiple prints from the stencils in said track including means to return the stencils along the tracks into a position to be again engaged and driven forwardly by said sectors. 17. A stencil printing machine including the combination of a stencil track, means to move stencils in successive order into said track, superposed driving and printing sectors disposed on opposite sides of said track in position to engage the stencils therein and drive them therealong while printing from the stencils, and means to make multiple prints from the stencils in said track including means to return the stencils along the track into a position to be again engaged and driven forwardly by said sectors and means to disable said stencil moving means prior to the operation of said stencil returning means. 18. A stencil printing machine including the combination of a stencil track, means to move stencils in successive order into said track, superposed driving and printing sectors disposed on opposite sides of said track in position to engage the stencils therein and drive them therealong while printing from the stencils, and means to make multiple prints from the stencils in said track including detachable means to return the stencils along the track into a position to be again engaged and driven forwardly by said sectors. 19. A stencil printing machine including the combination of a stencil track, means to move stencils in successive order into said track, superposed driving and printing sectors disposed on opposite sides of said track in position to engage the stencils therein and drive them therealong while printing from the stencils, and means to make multiple prints from the stencils in said track including stencil retrieving means arranged continually in engagement with the stencils in said tracks, and means to condition said retrieving means to operate to return a stencil backward along said track into a position to be again engaged by said sectors. 20. A stencil printing machine including the combination of a stencil track, means to move stencils in successive order into said track, superimposed driving and printing sectors disposed on opposite sides of said track in position to engage the stencils therein and drive them therealong while printing from the stencils, and means to make multiple prints from the stencils in said track including stencil retrieving means arranged continually in engagement with the stencils in said tracks, and means to condition said retrieving means to operate to return a stencil backward along said track into a position to be again engaged by said sectors, said conditioning means including means to disable said stencil moving means. 21. A stencil printing machine including the combination of a stencil track, means to move stencils in successive order into said track, superimposed driving and printing sectors disposed on opposite sides of said track in position to engage the stencils therein and drive them therealong while printing from the stencils, and means to make multiple prints from the stencils in said track including stencil retrieving means arranged continuously in frictional engagement with the stencils in said track and means to condition said retrieving means to operate to move a stencil backward along said track into a position to be again engaged by said sectors. 22. A stencil printing machine including the combination of a stencil track, means to move stencils in successive order into said track, superimposed driving and printing sectors disposed on opposite sides of said track in position to engage the stencils therein and drive them therealong while printing from the stencils, and means to make multiple prints from the stencils in said track including stencil retrieving means arranged continuously in frictional engagement with the marginal portions of the stencils in said track and means to condition said retrieving means to operate to move a stencil backward along said track into a position to be again engaged by said sectors. 23. A stencil printing machine including the combination of a stencil track, means to move stencils in successive order into said track, superimposed driving and printing sectors disposed on opposite sides of said track in position to engage the stencils therein and drive them therealong while printing from the stencils, and means to make

- multiple prints from the stencils in said track including stencil retrieving means arranged in engagement with the stencils in said track and constructed and arranged to 5 act upon the stencils in a direction to move them backward along said track against the action of said sectors and stencil moving means, and means to condition said retrieving means for retrieving operation including 10 means to disable said stencil moving means.
24. A stencil printing machine including the combination of a stencil track, means to move stencils in successive order into said track, superimposed driving and printing sectors disposed on opposite sides of said track in position to engage the stencils therein and drive them therealong while printing from the stencils, and means to make multiple prints from the stencils in said track including stencil retrieving means comprising a member having means to engage frictionally the stencils in said stencil track, means to guide said member for reciprocatory movement in the direction of stencil movement in said track, means to move said member into a position to re-present a printed stencil engaged by it for a second printing operation and means to condition said 30 member for operation.
25. A stencil printing machine including the combination of a stencil track, means to move stencils in successive order into said track, superimposed driving and printing sectors disposed on opposite sides of said track in position to engage the stencils therein and drive them therealong while printing from the stencils, and means to make multiple prints from the stencils in said track including stencil retrieving means comprising a member having means to engage frictionally the stencils in said stencil track, means to guide said member for reciprocatory movement in the direction of stencil movement in said track, forward and rear stop-members arranged to be engaged by said member and limit the extent of reciprocatory movement thereof, means to move said member against said rear stop-member and into a position to re-present a printed stencil engaged by it for a second printing operation, and means to condition said member for operation.
26. A stencil printing machine including the combination of a stencil track, means to move stencils in successive order into said track, superimposed driving and printing sectors disposed on opposite sides of said track in position to engage the stencils therein and drive them therealong while printing from the stencils, and means to make multiple prints from the stencils in said track including stencil retrieving means comprising a member having means through which 55 the stencils in said track are passed and engaged frictionally, said member having a stencil-engaging extent which does not substantially exceed the length of a stencil, means to guide said member for forward movement in a direction substantially parallel to the direction of movement of the stencils in said track, a forward stop-member arranged to engage and restrict the forward movement of said member in an engaging position with but one stencil in said track, 70 a rear stop member, means constantly urging said member and stencil therein contained toward said rear stop-member, and means to condition said member for operation.
27. A stencil printing machine including the combination of a stencil track, means to move stencils in successive order into said track, superimposed driving and printing sectors disposed on opposite sides of said track in a position to engage the stencils therein and drive them therealong while printing from the stencils, and means to make multiple prints from the stencils in said track including stencil retrieving means comprising a member arranged for sliding movement upon said track and having means through which the stencils in said track are passed and engaged frictionally, said member having a stencil-engaging extent which is not greater than the length of a stencil, a forward stop-member arranged to restrict the forward movement of said member by said stencils and hold it in engaging position with a single stencil, a rear stop-member, a spring connected with said member and arranged to urge it toward said rear stop-member whereby to return a stencil carried by it into position for reprinting, and means to condition said stencil retrieving means for operation.
28. A stencil printing machine including the combination of a stencil track, means to move stencils in successive order into said track, superimposed driving and printing sectors disposed on opposite sides of said track in position to engage the stencils therein and drive them therealong while printing from the stencils, and means to make multiple prints from the stencils in said track including stencil retrieving means comprising a member having opposed resilient arms adapted to engage and slide freely upon the stencil track, said arms extended inwardly into the stencil space in the track and having inwardly reflexed end-portions arranged yieldingly to engage the opposite marginal faces of the stencils in said track, the stencil-engaging end-portions of said arms having a stencil-engaging extent not greater than the length of a stencil, a forward stop-member adapted to restrict the forward movement of said member by the stencils in said track and hold said member in engaging position with 125 130

- a single stencil, a rear stop-member, a spring connected with said member and arranged to urge it toward said rear stop-member whereby to return a stencil engaged by it 5 into position for re-printing, and means to condition said stencil-retrieving means for operation including means to disable said stencil moving means.
29. In a stencil printing machine having 10 means to move stencils successively into and out of a printing position and simultaneously print from the stencils, a stencil retrieving device having means to grip each stencil as it moves into printing position with sufficient strength to return the stencils to the printing position, when such movement is not otherwise prevented, and to permit the stencils to be moved thereinto and there-through by the stencil-moving means.
30. A stencil printing machine having the combination of a stencil track, stencil printing means disposed in operative relation with the stencils in said track, a stencil holder disposed at one side of said printing 15 means and in position to deliver stencils to said track, means to deliver stencils in successive order from said stencil holder to said track, operating means for said printing means and delivery means, and means to condition said printing means for operation independently of said delivery means including means to render said stencil delivery means motionless.
31. A stencil printing machine having the combination of a stencil track, stencil printing means disposed in operative relation with the stencils in said track, a stencil holder disposed at one side of said printing 20 means and in position to deliver stencils to said track, means to deliver stencils in successive order from said stencil holder to said track, operating means for both said printing means and delivery means, and means to condition said printing means for operation independently of said delivery means comprising means to disconnect said delivery means from operative relation with 25 said operating means.
32. A stencil printing machine having the combination of a stencil track, stencil printing means disposed in operative relation with the stencils in said track, a stencil holder disposed at one side of said printing 30 means and in position to deliver stencils to said track, means to deliver stencils in successive order from said stencil holder to said track, common manual operating means for said printing means and delivery means, and means for operation independently of said delivery means comprising manual disabling means for said delivery means disposed for operation at said operating means.
33. A stencil printing machine having the combination of a stencil track, stencil printing 35 means disposed in operative relation with the stencil in said track, a stencil holder disposed at one side of said printing means and in position to deliver stencils to said track, reciprocable means to deliver stencils in successive order from said stencil holder to said track, operating means for both said printing means and delivery means, and means to arrest the reciprocatory movement of said delivery means and operate said printing means independently of said delivery means.
34. A stencil printing machine having the combination of a stencil track, stencil printing means disposed in operative relation with the stencils in said track, a stencil holder disposed at one side of said printing 40 means and in position to deliver stencils to said track, means to deliver stencils in successive order from said stencil holder to said track, including a pusher reciprocable below said stencil holder and arranged successively to engage the lowermost stencils in said holder and move them successively into said track, operating means for said pusher and manual means to arrest the movement of said pusher.
35. A stencil printing machine having the combination of a stencil track, stencil printing means disposed in operative relation with the stencils in said track, a stencil holder disposed at one side of said printing 45 means and in position to deliver stencils to said track, means to deliver stencils in successive order from said stencil holder to said track including a pusher reciprocable below said stencil holder and arranged successively to engage the lowermost stencils in said holder and move them successively into said track, common operating means for said pusher and printing means, and manual means to disconnect said pusher operatively from said operating means.
36. A stencil printing machine having the combination of a stencil track, stencil printing means disposed in operative relation with the stencils in said track, a stencil holder disposed at one side of said printing 50 means and in position to deliver stencils to said track, means to deliver stencils in successive order from said stencil holder to said track including a pusher reciprocable below said stencil holder and arranged successively to engage the lowermost stencils in said holder and move them successively into said track, common manual operating means for said pusher and printing means, and manual means located at said operating means arranged to disconnect said pusher operatively from said operating means, whereby to permit said printing means to be operated independently of said pusher.
37. A stencil printing machine having the combination of a stencil track, stencil printing 55 means disposed in operative relation with the stencils in said track, a stencil

- holder disposed at one side of said printing means and in position to deliver stencils to said track, means to deliver stencils in successive order from said stencil holder to said track, including a pusher reciprocable below said stencil holder and arranged successively to engage the lowermost stencils in said holder and move them successively into said track, operating means for said pusher, and printing means including a rotatable crank arm, a connecting rod connecting said crank arm and pusher, and manual means to disconnect said crank arm and connecting rod.
38. A stencil printing machine having the combination of a stencil track, stencil printing means disposed in operative relation with the stencils in said track, a stencil holder disposed at one side of said printing means and in position to deliver stencils to said track, means to deliver stencils in successive order from said stencil holder to said track, including a pusher reciprocable below said stencil holder and arranged successively to engage the lowermost stencils in said holder and move them successively into said track, operating means for said pusher, and printing means including a rotatable crank arm, a connecting rod connecting said crank arm and pusher, and a breakable connection between said connecting rod and crank arm.
39. A stencil printing machine having the combination of a stencil track, stencil printing means disposed in operative relation with the stencils in said track, a stencil holder disposed at one side of said printing means and in position to deliver stencils to said track, means to deliver stencils in successive order from said stencil holder to said track including a pusher reciprocable below said stencil holder and arranged successively to engage the lowermost stencils in said holder and move them successively into said track, operating means for said pusher, and printing means including a rotatable crank arm, a connecting rod arranged to connect said pusher operatively with said crank arm, said connecting rod having a hooked end portion arranged to engage said crank arm releasably, and yielding means arranged to secure said crank arm and connecting rod in releasable operative engagement.
40. A stencil printing machine having the combination of a stencil track, stencil printing means disposed in operative relation with the stencils in said track, a stencil holder disposed at one side of said printing means and in position to deliver stencils to said track, including a pusher reciprocable below said stencil holder and arranged successively to engage the lowermost stencils in said track, operating means for said pusher, and printing means including a rotatable crank arm, a connecting rod arranged to connect said pusher operatively with said crank arm, said connecting rod having a hooked end portion arranged to engage said crank arm releasably, and yielding means arranged to secure said crank arm and connecting rod in releasable operative engagement.
41. A stencil printing machine having the combination of a stencil track, stencil printing means disposed in operative relation with the stencils in said track, a stencil holder disposed at one side of said printing means and in position to deliver stencils to said track, means to deliver stencils in successive order from said stencil holder to said track, including a pusher reciprocable below said stencil holder and arranged successively to engage the lowermost stencils in said holder and move them successively into said track, operating means for said pusher, and printing means including a rotatable crank arm, a connecting rod arranged to connect said pusher operatively with said crank arm, said connecting rod having a hooked end portion arranged to engage said crank arm releasably, and yielding means arranged to secure said crank arm and connecting rod in releasable operative engagement.
42. A stencil printing machine having the combination of a stencil track, a stencil holder disposed above one end of said track, superimposed upper and lower sectors disposed at one side of said stencil holder and in position to engage the stencils in said track and move them therealong while printing therefrom, a pusher reciprocable beneath said stencil holder and arranged to remove the lowermost stencils from said holder and deliver them successively into said track in position to be engaged by said sectors, an operating handle arranged in driving relation with said sectors, a connecting rod connecting said operating handle and pusher, said connecting rod having a detachable connection with said operating handle, whereby said sectors may be rotated

independently of said pusher, and means to make multiple prints of the stencils in said track including a member slidable upon the track and having resilient arms between which the stencils in the track are moved and engaged yieldingly, said stencils arranged to move said member forwardly along said track, a forward stop member arranged to limit the extent of forward movement of said member, and a retractile spring connected with said member, operable upon the disabling of said pusher, to retract said member and the stencil carried by it toward said stencil holder and into a position to be again engaged by said printing sectors.

43. A stencil printing machine comprising the combination of a stencil track, intermittently operating means to deliver stencils successively into said track, intermittently operating means to engage and move the stencils along said track and at the same time print therefrom, means to make multiple prints from the stencils in said track including a member arranged continually to act upon the stencils in said track and move them backward therealong in position to be re-engaged by said printing means, and means to hold said stencils from backward movement in said track during the period of operation of said printing and delivery means.

44. A stencil printing machine comprising the combination of a stencil track, intermittently operating means to deliver stencils successively into said track, intermittently operating means to engage and move the stencils along said track and at the same time print therefrom, means to make multiple prints from the stencils in said track including a member arranged continually to act upon the stencils in said track and move them backward therealong in position to be re-engaged by said printing means, and means comprising a latch arranged yieldingly to engage the successive stencils in said track and hold them against backward movement in said track during the period of operation of said printing and delivering means.

45. A stencil printing machine comprising the combination of a stencil track, intermittently operating means to deliver stencils successively into said track, intermittently operating means to engage and move the stencils along said track and at the same time print therefrom, means to make multiple prints from the stencils in said track including a member arranged continually to act upon the stencils in said track and move them backward therealong in position to be re-engaged by said printing means, and means to disable said stencil delivery means and condition said member to move the sten-

cil engaged by it into position to be re-engaged by said printing means.

46. A stencil printing machine having the combination of a stencil track, means to feed stencils successively into said track, upper and lower sectors arranged to engage the stencils in said track and move them therealong and simultaneously print therefrom, and auxiliary printing means including superimposed upper and lower sectors, said upper sector having means removably to receive printing characters, inking means arranged in operative relation with said upper sector, and means to drive all sectors simultaneously.

47. A stencil printing machine having the combination of a stencil track, means to feed stencils successively into said track, upper and lower sectors arranged to engage the stencils in said track and move them therealong and simultaneously print therefrom, upper and lower operating shafts on which said sectors are mounted, and auxiliary printing means including superimposed upper and lower sectors carried by said operating shafts, means to secure said upper sector detachably to its operating shaft, said upper sector having means removably to receive printing characters, inking means arranged in operative relation with said upper sector, and means to drive all sectors simultaneously.

48. A stencil printing machine having the combination of a stencil track, means to feed stencils successively into said track, upper and lower sectors arranged to engage the stencils in said track and move them therealong and simultaneously print therefrom, a pivoted arm, upper and lower operating shafts on which said sectors are mounted, means to support said upper shaft rotatably in said arm, and auxiliary printing means including superimposed upper and lower sectors carried by said upper and lower shafts, said upper sector having means removably to receive printing characters, an ink roll journaled on said pivoted arm and disposed in operative relation with said upper auxiliary sector, and means to drive all sectors simultaneously.

49. A stencil printing machine including a printing device, means to deliver stencils in successive order to said printing device, means to operate simultaneously both said printing device and said delivery means including an operating handle common to both, and means to disable said delivery means including a disabling device carried by and manually operable at said operating handle.

In testimony whereof, I have signed my name to this specification.

HARMON P. ELLIOTT.
